UNITED STATES PATENT OFFICE.

ANTON C. EGGERS, OF NEW YORK, N. Y.

COMBINED TOILET ARTICLE.

No. 823,464.

Specification of Letters Patent.

Patented June 12, 1906.

Application filed July 14, 1905; Serial No. 269,743.

To all whom it may concern:

Be it known that I, ANTON C. EGGERS, a citizen of the United States, residing in New York, in the borough of Brooklyn and State 5 of New York, have invented certain new and useful Improvements in a Combined Toilet Article, of which the following is a specification.

This invention relates to a toilet article.

10 Combinations of hair-brushes, mirrors, and combs have been made heretofore, but without meeting with practical success, being rather cumbersome and inconvenient in use.

The object of this invention is to avoid 15 these defects and to provide a device of this kind in which the toilet articles referred to are combined in a particularly compact and convenient manner and in which such articles may be used independently of each other. 20 With these and other ends in view the invention consists in a device which embodies the novel features and combinations of parts which will be particularly described herein-after and finally pointed out in the claims.

25 In the accompanying drawings, Figure 1 is a perspective view of a toilet article or kit embodying the invention. Fig. 2 is a vertical longitudinal section of the same on line 2 2, Fig. 1. Fig. 3 is a perspective view of 30 the device for interclamping the mirror and brush, showing the comb positioned therein. Fig. 4 is a perspective view of the mirror shown as detached from the other parts of the device. Fig. 5 is a perspective view of 35 the brush proper, and Fig. 6 is a vertical transverse section on line 6 6, Fig. 1.

Similar letters of reference indicate corresponding parts throughout the different figures of the drawings.

40 Referring to the drawings, A denotes a hair-brush such as used in carrying out my invention, which is preferably of the usual type, with the exception that the back and handle thereof are rabbeted throughout their 45 peripheries in such a manner as to form a marginal or peripheral seat a. Upon the back of the brush A is fitted face down a mirror B, having a peripheral flange a' engaging the seat a and of the form shown in Fig. 4,

50 said mirror conforming throughout to the contour of the brush and carrying upon its face a mirror proper, B^X. The mirror B is provided with a recess d', extending longitudinally thereof from the mirror proper, B^X, to 55 the ends of the handle B', as shown in Fig. 4.

In order to interclamp the brush and mirror,

a holder C is employed, which is provided with a socket adapted to be snugly fitted over the ends of the handles A' B' of the brush and mirror, respectively, as shown in Fig. 1. This holder C is furthermore provided with an interior auxiliary holder C', forming a socket, which is adapted to receive the end of a comb D in such a manner that when said holder C is slipped over the handles of the brush and 60 mirror the comb D extends inwardly between said brush and mirror, fitting in the handle-recess d' of the latter, as shown in Fig. 2, and extending over the rear face of the mirror B^X, which is spaced from its back, as 65 shown. The holder C is preferably made of 70 spring metal in order to exert a firm clamping action on the handles of the brush and mirror and to thus serve, in connection with the marginal rabbet-joint, to detachably retain 75 these parts in fixed relation. The holder C', in which the comb is positioned, is also preferably formed of spring metal in order to exert a clamping action upon the comb and 80 firmly hold the same in its seat.

When the parts are assembled, as shown in Fig. 1, the device may be used as a brush in the usual manner, as will be readily understood. When it is desired to use the mirror, the holder C is slipped from the handles A' 85 and B', so that said mirror is released and can be held in one hand, while the other hand is used for holding the brush. In being withdrawn from the handles of the brush and mirror the holder C carries with it the comb D, 90 and the latter may then be used with said holder, forming a handle therefor, or it may be withdrawn from its socket in said holder. When it is desired to replace the parts, it is simply necessary to superpose the mirror 95 face down upon the back of the brush and then to interclamp the said parts by fitting the clamping-holder over the handles, the comb, which has previously been inserted into said holder, being inserted at the same 100 time into the recess upon the front face of the mirror-handle, and thus positioned between the mirror and brush.

All the parts can be readily separated and reassembled, and a very convenient combination toilet device is provided, which may be used either on the toilet-table or especially when traveling. The device is extremely compact, neat in appearance, and the different constituent parts may be used independently as conveniently as the separate articles.

Having thus described my invention, I

claim as new and desire to secure by Letters Patent—

1. In a toilet-kit, the combination of a brush provided with a handle, an independent mirror seated upon the back of said brush and likewise provided with a handle, said mirror and its handle conforming throughout to the contour of said brush and the handle thereof, and a single independent device for detachably retaining said parts in fixed relation.
2. A device such as described embodying a hair-brush provided with a handle, a mirror seated upon the back of said brush, and likewise provided with a handle, and a spring-metal holder detachably fitting over said handles and interclamping the same.
3. A device such as described comprising a hair-brush provided with a handle and having upon its back a marginal seat extending throughout the edge of the same and said handle, a mirror likewise having a handle and provided with a corresponding marginal flange engaging said seat, and a single device fitting over said handles for detachably clamping together said mirror and brush.
4. A device such as described comprising a hair-brush provided with a handle, a mirror likewise provided with a handle and seated upon the back of said brush by means of a marginal rabbet-joint extending throughout the edges or peripheries of said brush and mirror and the handles thereof, and means for interclamping said parts.
5. The combination of a hair-brush, a mirror, and an independent comb-carrying device for interclamping the same.
6. A hair-brush, a mirror, and a device for interclamping said articles embodying a spring-metal comb-seat, and a comb frictionally held at one end in said comb-seat.
7. In a toilet-kit, a hair-brush, a mirror superposed thereon, an independent device for interclamping said parts, and a comb carried at one end by said device and extending between said parts.
8. In toilet articles, a hair-brush, a mirror superposed on the back thereof, said brush and mirror being each provided with a handle, an independent device for clamping together said handles, and a comb carried by said clamping device and interposed between said handles.
9. The combination, with a hair-brush, of a mirror seated upon the back thereof, said brush and mirror being each provided with a handle, and a clamping device embodying a socket fitting over the ends of said handles and a separate comb-receiving socket.
10. The combination of a hair-brush provided with a handle, a mirror likewise provided with a handle and seated face down upon the back of said brush, said last-named handle being provided with a longitudinally-extending recess and the mirror proper being spaced at its rear face from its back, a comb disposed in said recess and extending between the mirror proper and its back, and means for holding said parts in fixed relation.
11. The combination, with a hair-brush provided with a handle, of a mirror likewise provided with a handle and fitting upon the back of said brush, the handle of said mirror being provided with a longitudinally-extending recess, a holder fitting over the ends of said handles, and a comb carried by said holder and fitting in said recess.
12. The combination, with a brush provided with a handle, of a mirror seated upon the back of said brush and likewise provided with a handle, the handle of said mirror being provided upon its lower face with a longitudinally-extending recess, a device for interclamping said handles embodying a socket fitting over the ends of the same and a comb seat or holder within said socket, and a comb held in said comb-seat and fitting in said recess.

In testimony that I claim the foregoing as my invention I have signed my name in presence of two subscribing witnesses.

ANTON C. EGgers.
